UNITED STATES PATENT OFFICE.

FRANCIS BLAKE, OF WESTON, MASSACHUSETTS.

SWITCH-BOARD FOR ELECTRIC CIRCUITS.

SPECIFICATION forming part of Letters Patent No. 243,839, dated July 5, 1881.

Application filed May 31, 1881. (Model.)

To all whom it may concern:

Be it known that I, FRANCIS BLAKE, of Weston, in the State of Massachusetts, have invented a new and useful Improvement in 5 Switch-Boards for Electric Circuits, of which the following is a specification.

The invention relates to that form of switch-board which contains two series of metallic rods, one crossing the other, each rod of one 10 series being in a separate line or circuit, while each rod of the other series may be used to make a connection between any two line rods or circuits.

The object of my invention is to increase the 15 number of rods of one of the series within a given space, and this has been accomplished by sawing slots with a fine saw across the face of a board, as near together as may be, and each of such width and depth that it may be 20 substantially filled by an exceedingly fine wire, and then filling said slots with such wires.

Accordingly the invention consists in a 25 switch-board having two series of rods insulated from each other, one series embedded in slots across the face of the board and the other series crossing the embedded rods and provided with contact-pins, as hereinafter set forth.

In the drawings, Figure 1 is a plan of so 30 much of a switch-board as is sufficient to illustrate my invention, Figs. 2 and 3 being respectively longitudinal and cross sections of the same. Figs. 4, 5, and 6 are corresponding views of a modified form of switch-board embodying the said invention.

When the switch-board is constructed according to Figs. 1, 2, and 3 both series of rods are fixed or stationary, and connection is made 35 between any rod of one series and any rod of the other series by means of a sliding pin, one of which is upon each rod of one of the series. When the construction of Figs. 3, 4, and 5 is followed one series of rods has a sliding motion over the other series, each sliding rod carrying 40 a pin which may be forced into contact with any rod in the other series.

Confining the description for the present to the first-mentioned form of construction, A is the table or board proper, and *r r r*, &c., are 45 insulated connecting-rods embedded in the table, as shown. *R R* are line-rods, and *P P* contact-pins, supported each in a small bracket, *b*, sliding on one of the rods *R*, a coiled spring

tending to keep the pin in contact with the table, or with any rod *r* embedded therein. I 55 have shown but two line-rods, all the rest being of the same construction, and each having a bracket, *b*, and pin *P*.

It is evident that the pin *P* can be moved any required distance on the rod *R*, and that 60 it may be made to touch any connecting-rod *r* without touching any other, however small the distance between two connecting-rods. Accordingly I use fine wires for the connecting-rods, laying them from seven to ten to every 65 inch of table, each wire in a slot cut across the board by a saw of a gage corresponding to that of the wire.

The board proper shown at Figs. 4, 5, and 6 differs from the one above described in having a series of slots, *s*, at right angles to the connecting-rods and extending to some distance below them. In these figures, as in the others, *A* is the board, and *r r r*, &c., the connecting-rods. *R' R'* are two line-rods, and *P' P'* 70 contact-pins; but here the line-rods *R' R'*, instead of being stationary, slide over the connecting-rods, and the pins *P'* have a motion in the sliding rods to and from the board and connecting-rods, the coiled springs tending to 75 keep them out of contact with the latter. The slots *s* permit the pins *P'* to be pushed in between any two rods, *r*, and when so pushed in a spring, *t*, upon the sliding rod that carries the pin causes the pin to bind against one of 80 the connecting-rods in the manner set forth in an application for a patent filed by me May 9, 1881.

In the present state of the art it is unnecessary to show or refer especially to the line and ground connections or to describe the mode of operation; and it is evident the rods *r* might be placed in the lines or circuits and the rods *R* or *R'* used as connecting-rods without departing from my invention.

I claim—

A switch-board provided with two series of rods insulated from each other, one series embedded in slots across the face of the board, while each rod of the other series is provided 90 with a contact-pin and crosses every rod of the embedded series, substantially as described.

FRANCIS BLAKE.
